Des. 201,904
Patented Aug. 10, 1965

201,904

DETACHABLE HANDLE FOR SAUCEPANS OR THE LIKE

Edward D. Levy, Spring Valley, N.Y., assignor to Owens-
Illinois Glass Company, Toledo, Ohio, a corporation of Ohio

Filed June 25, 1964, Ser. No. 80,584

Term of patent 14 years

(Cl. D44—29)

FIG. 1

FIG. 2

FIG. 3

FIG. 5

The ornamental design for a detachable handle for saucepans or the like, substantially as shown.
